UNITED STATES PATENT OFFICE.

JOHAN EILERT ORVIN, OF CHRISTIANIA, NORWAY.

SUPPORT-STRAP FOR REINFORCEMENT IN STEEL-CONCRETE GIRDERS.

1,342,349.

Specification of Letters Patent.

Patented June 1, 1920.

Application filed January 29, 1919. Serial No. 273,928.

To all whom it may concern:

Be it known that JOHAN EILERT ORVIN, civil engineer, subject of Norway, Oscars Gate 78, Christiania, Norway, have invented new and useful Improvements in Support-Straps for the Reinforcement in Steel-Concrete Girders, of which the following is a specification:

In the casting of combined steel and concrete girders, it is very important that the iron reinforcement should be held securely in its fixed position. The iron bars were heretofore often equipped with projections in convenient places, which were supported by the mold or casing whereby the bars were held in their proper position.

Many drawbacks were caused by these projections and several attempts have been made to overcome these disadvantages without giving the result wanted.

The present invention has for its object to provide a metal strap, which is formed in such a way that it may be easily placed in the mold box and may at once serve as a support for the reinforcement bars without any special measures being necessary when manufacturing these bars.

The invention is shown in the accompanying drawing in which:

30 The figure shows the support strap in position in the mold box of a common steel concrete girder in a floor.

As shown in the drawing, the U-shaped strap 1 is equipped with loops 2 resting on the mold 3, for keeping especially the central part or cross-head 7 of the strap at a fixed distance from the bottom of the mold. The reinforcement bars 4 may be placed directly upon the central portion of the strap and be held in this position during the casting of the concrete girder.

For reinforcing very broad girders, the central part of the strap may also be

equipped with a loop 5 as shown by dotted lines.

The strap has its upper ends bent downwardly to provide legs 6, which rest on the upper portion of the mold alongside of or over the concrete girder. These legs support the strap in a fixed vertical position 50 in the concrete box, without any further supporting means.

Such straps are placed at convenient intervals, for instance at each half meter of the length of the girder.

It will be noted that the loops 2 extend outwardly from the lower corners of the strap and that they rest in the corners of the mold, so that said loops will serve to space the sides and bottom of the strap 60 from the sides and bottom of the mold. By placing the loops at the corners of the strap, a saving in material will be effected, as it will not be necessary to provide additional projections from the strap sides. 65 The elimination of additional side projections will also save the effort and time required in forming such loops.

Having now described my invention, what I claim as new and desire to secure by Letters Patent is:—

A stirrup for supporting reinforcing bars for concrete comprising a single piece of wire bent to provide a cross-head having its ends bent to form outwardly extending 75 loops which merge into parallel side members having their upper ends bent to form supporting legs, said loops being designed to rest in the corners of a mold for spacing the cross-head away from the bottom of the 80 mold and the side members away from the sides of the mold.

In testimony whereof I have signed my name to this specification.

JOHAN EILERT ORVIN.
